UNITED STATES PATENT OFFICE.

OSMOND GILLES BLUNDEN, OF LONDON, ENGLAND.

APPARATUS FOR PREPARING PEAT FOR FUEL.

SPECIFICATION forming part of Letters Patent No. 506,151, dated October 3, 1893.

Application filed February 9, 1893. Serial No. 461,592. (No model.) Patented in England December 8, 1891, No. 21,481.

To all whom it may concern:

Be it known that I, OSMOND GILLES BLUNDEN, engineer, a subject of the Queen of Great Britain, residing at No. 180 Cambridge street, 5 Warwick Square, in the county of Middlesex, England, have invented new and useful Improvements in Apparatus for and the Method of Preparing Peat and Turf for Use as Fuel, (for which Letters Patent of Great Britain 10 have been granted me bearing date the 8th day of December, 1891, No. 21,481,) of which the following is a specification.

Hitherto peat or turf when required for fuel has been simply pugged or ground and shaped 15 into solid blocks and dried.

Now my invention consists in macerating and cutting the fibers and compressing the peat or turf into hollow cylindrical blocks, tubes, or other forms in order to accelerate 20 the process of drying and condensing and also to aid the combustion of the fuel.

In order that my invention may be more fully understood and carried into practice I will now proceed to describe the same with 25 reference to the accompanying drawings, of which—

Figure 1 represents a side elevation of a machine constructed according to this invention; Fig. 2 an end elevation of the same, and Fig. 30 3 a horizontal section taken across the center of the drum or cylinder of the apparatus. Figs. 4 and 5 represent detached parts of the said apparatus, and Fig. 6 is an end view of the drum or cylinder.

Similar reference letters are employed to indicate the same parts in all the figures of the drawings.

In carrying this invention into practical effect I employ a cutting and compressing machine as shown in the drawings consisting of a screw blade *a* and cutting knives *e* rotating within a drum or cylinder *b* provided with a hopper *c* for the introduction of the peat to be treated. The end of this cylinder into 45 which the peat first passes is provided with a number of longitudinal or spiral ribs or ridges *m* on its interior against which the peat is pressed and to a great extent broken up in its passage through the apparatus. The delivery end of the cylinder *b* I construct of taper form and make the screw blade *a* of gradually decreasing diameter where it lies within

this taper portion of the cylinder. The spindle or axis *d* of the screw blade *a* is extended beyond the said screw blade in order to act 55 as a revolving core to form the central opening in the peat blocks.

Between each adjacent set of knives *e* (which are shown separately at Fig. 4) is placed a wheel-like support *f* (shown separately at Fig. 5) the periphery of which is secured to the drum or cylinder *b*. The radial arms of these supports are each formed with a suitable shearing edge and the cutting blades *e* having similar shearing edges, revolving almost in contact with the same act with them to shear the fibers of the peat passing through the machine. I have found in practice that the best results are obtainable when the shearing blades or cutters have faces lying at right 60 angles to one another. The screw blades *a* feed the peat forward between the knives, by which its fibers are finely divided, into the taper portion of the cylinder. Here it is compressed by reason of the said taper form of 65 the same and is ejected at the outlet at the end of the same in the form of a tube, the central aperture in which is formed by means of the core *d* as previously described. The continuous tube of peat thus delivered from 70 the outlet of the machine is divided into lengths in the following manner:—Immediately under the said outlet of the machine is an endless band *g* supported upon pulleys and capable of movement in the direction of 75 the movement of the peat. The peat resting upon this band gives motion to it so that the two advance together, the band forming as it were a movable support for the peat tube.

The rotary cutter blade *h*, having a similar 80 cutting edge to those already described, is mounted upon an axis journaled immediately above the outlet of the cylinder *b* and driven by any suitable gear (such for example as that shown in Fig. 1) so that it may pass 85 across the said opening in the cylinder *b* at intervals and sever the protruding portion of the peat tube from that within the machine. A suitable roller *j* is mounted at the extremity of a rotating arm also pivoted over the 90 outlet of the cylinder and caused to rotate at the same axial speed as the blade *h* which it follows across the outlet of the cylinder *b*. This roller *j* strikes against the newly de-

tached portion of the peat tube and starts it rolling down an inclined board *k* from which it may be removed by hand or otherwise. In some cases I support the board or boards *k* on 5 rollers or pulleys *l* (Fig. 2) so that they may be drawn forward to make place for others. In this case the table *k* may with advantage consist of an endless band or belt. For supporting the peat tubes during the process of 10 drying I employ a number of wires stretched in horizontal pairs one above the other in the manner of telegraph wires. The peat tubes are laid upon these so that they are only supported at two points each and however closely 15 they are placed they can only touch one another along one line, this is of course owing to their cylindrical shape. This shape combined with the aperture through their center greatly accelerates the process of drying and 20 condensing.

Having now particularly described and as-

certained the nature of my said invention and in what manner the same is to be performed, I declare that what I claim is—

In a machine for preparing peat or turf for 25 fuel, the combination of a suitable casing, partly cylindrical and partly conical, provided with longitudinal ribs *m*, inside one end only, rotary knives or cutters *e* having broad cutting edges, fixed cutting blades *f* against 30 which the cutting edges of said knives or cutters *e* act, and a screw *a* part of which is tapered and the end of the axis of which forms a revolving core, substantially as and for the purposes herein before set forth.

OSMOND GILLES BLUNDEN.
